UNITED STATES PATENT OFFICE.

LORAN F. DOEN, OF CLEVELAND, OHIO, ASSIGNOR TO THE CLEVELAND HEATER COMPANY, OF CLEVELAND, OHIO, A CORPORATION OF OHIO.

WATER HEATER.

Application filed November 11, 1924. Serial No. 749,173.

This invention relates to improvements in water heaters for hot water systems the present embodiment relating more particularly to the base or burner carrying portions of 5 such hot water heaters used in such systems.

The invention further relates to the form and arrangement of the bottom portion of the heater body or jacket, together with an improved form of burner carrying base adapted to be quickly attached to or detached from the body of the heater and to swivel on the latter when attached, the improved swivel base being of particular advantage in connecting up or leading in the gas conduits or 10 connections from any angle to the mixer or Bunsen burner portion of the base, as distinguished from the ordinary hot water heater where the point of gas inlet or connection is relatively fixed.

20 The invention further relates to an improved detachable swivelly connected burner supporting base embodying integral Bunsen burner and drip pan members adapted to readily receive and support a suitable burner 25 within the base portion of the water heater body or jacket.

With the above mentioned and other ends in view, the invention consists in the novel construction, arrangement and combination 30 of parts, hereinafter described, illustrated in one of its embodiments in the accompanying drawings, and particularly pointed out in the appended claims.

Referring to the drawings, forming a part 35 of this specification, Figure 1 is a fragmentary central vertical sectional view of the base or burner portion of a hot water heater constructed in accordance with this invention.

40 Fig. 2, a horizontal cross sectional view, taken on line 2—2 of Fig. 1, a portion of the burner head being broken away for the purpose of clearer illustration of the subjacent parts.

45 Similar numerals of reference designate like parts throughout all the figures of the drawings.

The heater body or jacket is preferably of 50 general cylindrical form and comprises, in the present instance, a relatively fixed section 1, of general semi-cylindrical form, and a relatively movable or hinged section 1^a provided with hinges 1^b, adapted to be opened

outwardly for affording access to the interior water heating coils 1^m and burner head 4 55 when occasion arises.

The heater body or jacket made up of the sections 1 and 1^a is provided with an open bottom adapted to removably receive and contain the burner and burner supporting 60 base and drip pan, hereinafter referred to.

As a means of quickly attaching or detaching the supporting base, and particularly as a means of circumferentially shifting or 65 swivelling the supporting base for bringing the Bunsen burner or gas inlet mixing pipe to variable positions for the purposes herein mentioned, a swivelling connection or joint between the heater body and burner supporting 70 base is provided.

As a means of providing such swivel joint or connection, the base of the heater body or jacket is provided with a flanged rim 1^b, made up of an annular internal recess 1^c, and terminating in an annular inwardly extending 75 flange 1^d having an upper angularly disposed face 1^e.

The detachable or swivelling base 2 is provided with a raised seat 2^m at its border concentric to a companion or complementary 80 flanged rim 2^a, consisting of a complementary outer annular recess 2^b, and an outwardly projecting overlying annular flange 2^c. The lower face 2^k of the recess 2^b constitutes a supporting shoulder of the flange 1^d of the 85 jacket. The upper face 2^l of the recess 2^b is angularly disposed with respect to the face 2^k. When the parts are in assembled or nested relation, it will be seen that the flanged rims 1^b and 2^a interlock with each 90 other and will permit the supporting base and connected parts to be rotated or swivelled relatively of the heater body or fixed section 1 of the jacket.

As a means of removably securing or attaching the supporting base 2 in assembled relation, and particularly as a means of permitting such base to be swivelled or adjusted relatively of the fixed section and of holding such swivel base in interlocking swivelling 95 relation to the fixed section when the hinged or door section 1^a is open, an internal lug 1^e is provided, said lug 1^e being preferably provided with a recess or pocket 1^f, adapted to receive the upper end of a clamp plate 3, 100 extending downwardly to engage the inner 105

periphery of the flanged rim 2^a of the supporting base, said clamp 3 being removably and adjustably secured by means of a clamp screw or bolt 3^a and a nut 3^b, the latter being preferably seated in a nut receiving recess or pocket 1^c, on the exterior portion of the relatively fixed section 1 of the jacket. The angular relation of the contact portions 1^b and 2^b of the rims 1^b and 2^a exert a wedging action upon each other when they are clamped together and serve to hold the heater casing and base in rigid engagement with each other in the desired position.

The swivel base, in the present instance, is provided with an integral Bunsen burner, mixer or gas supply pipe 2^a, terminating at the center of the swivelling base in an upwardly extending tapered inlet or hub portion 2^b, for convenient attachment to the hub or head portion of a suitable burner head or body 4. The swivel head is also preferably provided with an integral drip and evaporating pan 2^c, connected or suspended, in the present instance, by means of radially extending arms 2^d. In the present instance, the supporting base 2 is provided with a depending skirt or rim portion 2^e, the latter being provided at suitable intervals with supporting legs 2^f. As heaters of this general type are generally supported or suspended at one side of the storage or hot water tank and some distance above the base or floor line, it will be understood that the legs 2^f are merely used for temporarily supporting the heaters when in storage or unattached in the heating system. Under these conditions it will be apparent from the construction of the swivel base that the heater casing will be supported by the raised border 2^m of the supporting base 2.

By reason of the above construction it will be obvious that the swivel base may be turned circumferentially by moving from right to left, using, for example, the projecting end of the Bunsen burner or mixer pipe 2^a as a handle so that the inlet pipe or connection to the gas inlet or mixer tube portion of the burner may be lined up at any convenient angle to the gas pipes previously installed.

Having thus described one of the embodiments of the invention, without having attempted to set forth all the forms in which it may be made, or all the modes of its use, what is claimed is:

1. A water heater assembly comprising an integral supporting base having a supporting shoulder and an outer supporting rim terminating at its upper edge in an outwardly extending flange overlying an annular groove and said supporting shoulder, a drip pan having an upstanding edge portion connected at intervals to said supporting rim to provide ventilating apertures therebetween, a fuel supply tube formed integrally with said pan and terminating in a fuel supply port con-

centric of said pan, and a cylindrical casing having an inwardly extending flange formed along its lower edge portion said annular groove being adapted to receive said inwardly extending flange to thereby provide an interlocked swivel connection between said casing and said base. 70

2. A water heater comprising a cylindrical casing, a base making swivel connection with said casing, a drip pan formed integrally with said base, a gas burner element integrally formed with said drip pan and having a body portion extending in the general direction of the plane of said pan, a heat producing burner connected to said burner element and directly overlying said pan, and supporting feet for said structure formed integrally with said base. 80

3. A water heater assembly comprising an integral supporting base having a supporting shoulder and an outer supporting rim terminating at its upper edge in an outwardly extending flange overlying an annular groove and said supporting shoulder, a drip pan having an upstanding edge portion connected at intervals to said supporting rim to provide ventilating apertures therebetween, a fuel supply tube formed integrally with said pan and terminating at one end in a fuel supply port concentric with the pan, and a cylindrical casing having an inwardly extending flange formed on its lower edge portion adapted to be received in said annular groove to thereby provide an interlocked swivel connection between said base and said casing, said casing being divided into two semi-cylindrical portions, one of which is movable relative to the other and one of said portions being clamped to said base by a connector adapted to engage the inner face 95 of the upper edge of said outer supporting rim, and a burner mounted on said fuel supply port. 100

4. A water heater assembly comprising an integral supporting base having a supporting shoulder and an outer supporting rim terminating at its upper edge in an outwardly extending flange overlying an annular groove and said supporting shoulder, a drip pan having an upstanding edge portion connected at intervals to said supporting rim to provide ventilating apertures therebetween, a fuel supply tube formed integrally with said pan and having its body portion extending in the direction of the plane of the pan, and a cylindrical casing having an inwardly extending flange formed on its lower edge portion adapted for reception in said annular groove to thereby provide an interlocked swivel connection between said base and said casing, said casing being divided into two semi-cylindrical portions, one of which is movable relative to the other and one of said portions being clamped to said base by a connector adapted to engage the inner face 115 of the upper edge of said outer supporting rim, and a burner mounted on said fuel supply port. 120

5. A water heater assembly comprising an integral supporting base having a supporting shoulder and an outer supporting rim terminating at its upper edge in an outwardly extending flange overlying an annular groove and said supporting shoulder, a drip pan having an upstanding edge portion connected at intervals to said supporting rim to provide ventilating apertures therebetween, a fuel supply tube formed integrally with said pan and having its body portion extending in the direction of the plane of the pan, and a cylindrical casing having an inwardly extending flange formed on its lower edge portion adapted for reception in said annular groove to thereby provide an interlocked swivel connection between said base and said casing, said casing being divided into two semi-cylindrical portions, one of which is movable relative to the other and one of said portions being clamped to said base by a connector adapted to engage the inner face 130 of the upper edge of said outer supporting rim, and a burner mounted on said fuel supply port. 135

- of the upper edge of said supporting rim, and a burner for said fuel supply port.
5. A water heater assembly comprising an integral supporting rim terminating in an outwardly extending annular flange, a drip pan having an upstanding edge portion connected to said supporting rim at intervals to provide ventilating apertures therebetween, a fuel supply tube extending in the general direction of the plane of said pan and formed integrally therewith and terminating at its inner end in an upstanding fuel supply port, and a cylindrical casing having an internal annular groove formed in its lower marginal edge portion adapted to receive said outwardly extending annular flange of said base to thereby provide an interlocking swivel connection between said base and said casing, said casing being provided with an outwardly movable section of substantially semi-cylindrical form.
6. A water heater assembly comprising a supporting base having an outer supporting rim, a drip pan connected thereto at intervals that provides ventilating apertures between said pan and said rim, a fuel supply pipe extending across the face of said pan and opening into an upstanding fuel supply port disposed centrally of said pan, said fuel supply tube being integrally formed with said pan and integrally connected to said supporting rim, a cylindrical casing connected by a swivel joint to said base and having an outwardly movable door portion of substantially semi-cylindrical form adapted to give access to the interior of said casing.
7. A water heater comprising a base having a rim portion, a drip pan having an upstanding edge portion integrally connected at intervals to said rim to provide ventilating apertures intermediate the drip pan and the rim, said drip pan being disposed entirely within the confining planes of said rim, a fuel supply element formed integrally with said drip pan, and a burner disposed on the inner end of said fuel supply element adapted to transmit heat to said drip pan, and a heater casing removably connected to said base.
8. In a water heater assembly a heater casing comprising a fixed and a relatively movable section, a unitary skirted base member, drip pan and gas supply conduit, cast in one piece and means to secure said unitary skirted base member to the fixed section of said heater casing.
9. An attachment unit for a heater casing, consisting of a supporting base having a drip collecting and evaporating pan formed integrally therewith and suspended from the top thereof and having a raised seat at its border for said casing.
10. A unitary base attachment for a heater casing containing water circulating elements, comprising a supporting base having an integral evaporating pan for collecting drippage from said elements and provided with integral means at its border adapted to permit said unit to be detachably connected to the lower part of said heater casing.
11. A base unit for a heater casing containing water circulating elements, comprising a gas supply pipe having a shallow drip pan cast integrally therewith and an annular seat for said casing integrally connected to said drip pan and said gas supply pipe.
12. In a gas fuel water heater, a fuel supply and mixer member, comprising a conduit having a horizontally extending mixing and feeding portion terminating in an upwardly extending neck adapted to lie at the center of the heater and to support a burner, and a pan formed integral with said member and concentric with its neck and extending horizontally at the level of said mixing portion.
13. An attachment unit for a heater casing, consisting of a supporting base having a gas supply conduit and a drip collecting and evaporating pan formed integrally therewith and suspended from the top thereof and having a raised seat at its border for said casing.
14. In a water heater assembly, a heater casing comprising a fixed and relatively movable section, an inwardly extending flange formed on the lower edge portion of said casing, a unitary skirted base member, drip pan, and gas supply conduit cast in one piece and means cooperating with said inwardly extending flange to secure said unitary skirted base member to the fixed section of said heater casing to provide an interlocked swivel connection between said casing and said base.

In testimony whereof I have affixed my signature.
